United States Patent

Des. 235,749
Patented July 8, 1975

235,749

ALARM CONTAINER

Joseph T. Sullivan, Huntingdon Valley, Pa., assignor to
Standard-Farrington Alarm & Signal Corp., Trevose,
Pa.

Filed Oct. 12, 1973, Ser. No. 405,779

Term of patent 14 years

Int. Cl. D29—02

U.S. Cl. D10—121

Fig. 1

Fig. 2

Fig. 3

Fig. 5

Fig. 4

FIG. 1 is a front perspective view of an alarm container showing my new design;

FIG. 2 is a top plan view thereof on a reduced scale;

FIG. 3 is a left side elevational view thereof on a reduced scale;

FIGS. 4 and 5 are front and rear elevational views respectively on a reduced scale.

The cross-hatching appearing in FIGS. 1 to 4 inclusive indicates a mesh construction and is not intended to indicate any particular color.

I claim:

The ornamental design for an alarm container, as shown and described.
